United States Patent Office

Des. 189,312
Patented Nov. 22, 1960

189,312

FINGER RING

Hyman Frackman, 16 N. Broadway, White Plains, N.Y.

Filed Apr. 21, 1960, Ser. No. 60,265

Term of patent 3½ years

(Cl. D45—10)

FIG.1

Fig. 1 is a front elevational view of a finger ring showing my new design;

Fig. 2 is a side view thereof; and

Fig. 3 is a top view thereof.

I claim:

The ornamental design for a finger ring, substantially as shown.
